ATTORNEY

UNITED STATES PATENT OFFICE.

DANIEL SCHUYLER, OF NEW YORK, N. Y.

MUSIC-CABINET.

SPECIFICATION forming part of Letters Patent No. 289,569, dated December 4, 1883.
Application filed April 5, 1883. (No model.)

To all whom it may concern:

Be it known that I, DANIEL SCHUYLER, of the city, county, and State of New York, have invented certain new and useful Improvements in Music-Cabinets, of which the following is a specification.

This invention has reference to an improved cabinet for storing sheet-music, newspapers, pictures, or similar articles, in which a series of swinging racks may be thrown into raised or lowered position for conveniently storing, removing, and inserting sheet-music, &c.

The invention consists of a casing open at the top and front, and provided with a step-shaped interior bottom, to each step of which a holder or rack is hinged in such a manner that one or more of them can be swung into raised or lowered position, they being then supported by the next adjoining racks. The front rack or panel is hinged to the bottom of the casing, and supported, when in lowered position, on sliding bracket-pins, which are drawn out simultaneously with the lowering of the front rack by means of suitable wire and spring connections with the casing and returned into their sockets in the bottom of the casing when the front rack or panel is raised. The wire and spring connections also hold the front rack or panel in position when raised.

In the accompanying drawings, Figure 1 represents a perspective view of my improved music-cabinet, shown as supported on suitable wall-brackets. Figs. 2 and 3 are vertical transverse sections of the same, showing it, respectively, with the racks in raised position and part of the racks thrown into lowered position; and Fig. 4 is a plan partly in horizontal section on line *y y*, Fig. 2.

Similar letters of reference indicate corresponding parts.

Referring to the drawings, *A* represents the casing of my improved music-cabinet, which may be made of any suitable material, size, and finish, and supported either by brackets on the wall or by legs or casters on the floor, or as a portable cabinet on the top of the piano, or in any other suitable manner. The casing *A* is open at the top and front, and provided with a regular bottom, *A'*, and an interior step-shaped bottom, *A''*. In place of the same, step-shaped side supports may be used. To

each step of the interior bottom, *A''*, is hinged a rack, *B*, which is provided with a rectangularly-extending L-shaped rest, *B'*, at the lower part, which portion is equal in width to the height of the individual steps of the bottom *A''*. For this reason the rest *B'* of each rack serves, when the latter is thrown into lowered position, as a support for the next adjoining rack above, so as to hold the latter in horizontal position. The front rack, *B*, forms also the front panel of the cabinet, and is also provided with a rest, *B'*, and hinged to the bottom *A'* of the casing, and supported in horizontal position, when thrown down, by sliding bracket-rods *D*, which are guided in socket-holes *d d* of the bottom *A'* of the casing *A*. The sliding bracket-rods *D* are moved simultaneously forward or back in their socket-holes *d d* by the lowering or raising of the front panel, *B*, which is accomplished by means of cords or wires *e*, that are attached to suitable points at the sides of the front panel, *B*, and connected to the rear ends of the bracket-rods *D*. The latter are connected to spiral or other suitable springs, *E*, of proper strength, which draw the sliding bracket-rods *D* back and to retain the front panel in closed position when raised. The step-shaped interior bottom, *A''*, is recessed or somewhat shortened at the ends, as shown at *e*, Figs. 2 and 3, so that the connecting cords or wires *e e* can pass from the front panel, *B*, to the rear end of the bracket-rods *D*. The bottom *A'* is provided with a longitudinal slot, *d'*, directly above each socket-hole *d*, in which slit a fixed staple or pin, *d''*, of the bracket-rod *D* is guided, to which staple the wires or cords *e e* are attached. The actuating-springs *E* also pass through the slots *d' d'*, as shown in Figs. 2 and 3, and are attached to the rear ends of the bracket-rods *D*.

The racks *B* are retained in raised position parallel to the rear wall of the casing *A* by means of spring-catches or other fastening devices, *f*, applied thereto and to the side walls of the casing *A*. These fastening devices prevent the oscillating of the racks and retain the music or other articles placed on the same in a reliable and uniform manner. They serve simply for the purpose of holding the racks *B* in vertical position; but do not prevent the ready lowering of the same when they are to be thrown into horizontal position, so as to

remove or insert the music. Any part or all of the racks may be thrown into horizontal position by one motion and returned again in the same way into their normal raised position, as will be clearly seen by reference to Figs. 2 and 3. By the different racks the music may be readily classified, songs being placed in one rack, marches in another, and so on. A double cabinet may be produced by arranging two of the single cabinets back to back, or one below the other. Sheet-music or other articles stored in the cabinet are preserved in a better manner and instantly within reach for use. It may be used as a music-stand by performers by throwing down one or more of the racks and supporting the music thereon.

The cabinet has the further advantage that the music is not required to be removed from the racks while making selections, as they themselves serve as supports when lowered.

The cabinet may be covered at the top in any suitable ornamental manner, either by a lid or by a piece of embroidered or other fabric.

Having thus described my invention, I claim as new and desire to secure by Letters Patent—

1. A music-cabinet consisting of a casing open at the front and provided with an interior step-shaped bottom or supports, and of racks hinged to the steps of said bottom or supports, and means for retaining them in an upright position, substantially as set forth.

2. The combination of the casing open at the front and having an interior step-shaped bottom, racks hinged to the steps of said bottom and provided with rests, said rests being equal in width to the height of the steps of the bottom, so as to form when in lowered position supports for the next adjoining racks, substantially as described.

3. The combination of a casing open at the

front and having a step-shaped interior bottom, racks hinged to the steps of said bottom and provided with rests, as described, and means, substantially as set forth, for supporting the front rack or panel in a horizontal position.

4. The combination of the casing A, having an interior step-shaped bottom, A², racks B, hinged to the steps of the bottom A², and provided with rests B', sliding bracket-rods D D, means, substantially as described, connecting the front rack, B, and the bracket-rods D D, and tension-springs, whereby they are moved forward or backward when the front panel is lowered or raised, substantially as specified.

5. The combination of the casing A, having an interior step-shaped bottom, A², racks B, hinged to the steps of the bottom A², bracket-rods D, carried in sockets of the casing, cords 6 or wires e e, connecting the front rack with the bracket-rods, and tension-springs E, attached and connected to the rear ends of the bracket-rods, substantially as set forth.

6. In a music cabinet, the combination, with the casing A, of a hinged front rack or panel, B, bracket-rods D D, carried in socket-holes of the casing, cords or wires e e, connecting said front rack with the bracket-rods, and tension-springs E E, located and connected as described, whereby the forward or backward motion of the bracket-rods is produced simultaneously with the lowering or raising of the front rack, substantially as described.

In testimony that I claim the foregoing as my invention I have signed my name in presence of two subscribing witnesses.

DANIEL SCHUYLER.
